UNITED STATES PATENT OFFICE.

ARNOLD AUGUST EGLI, OF HAMBURG, GERMANY, ASSIGNOR TO THE FIRM: CHOCOLAT TOBLER HOLDING CO., AKTIENGESELLSCHAFT, OF SCHAFFHAUSEN, SWITZERLAND.

APPARATUS FOR REGISTERING THE WRITING OR CASTING POSITION OF LINE-FOR-LINE-PRINTING TYPEWRITERS, TYPESETTING MACHINES, OR THE LIKE.

Application filed May 6, 1926, Serial No. 107,180, and in Germany May 12, 1925.

The invention relates to line-printing typewriters, type-setting machines or the like, in which the writing or casting position of a line is first preparatorily adjusted and the transference of the type into the writing or casting position only takes place after the key actuation of a whole line.

The invention consists more particularly in the fact that one or more mechanisms receiving preparatory registrations during the separate key depressions, after the key actuation of a line or of part of a line, deliver the registrations in their entirety to other mechanisms adapted for the reception of registrations, and these mechanisms then form the medium of the final transference of the type into the writing position or deliver their registrations to other mechanisms adapted for the reception of registrations.

20 The mechanisms which deliver the preparatory registrations preferably consist, like the mechanisms receiving the said registrations, of levers which after the delivery of the registrations can be immediately brought back by a releasing plate or the like to their original positions, being thereby made ready for the reception of fresh registrations.

The mechanisms that receive the preparatory registrations from the keys are preferably moved after the key actuation of a line, in their entirety, by the motor drive, towards the mechanisms receiving these registrations, and thus give up their registrations. The moving of these mechanisms may preferably be effected by means of frames provided on the exterior of the machine, equipped with oblique slots and moved by the motor.

40 Apparatus according to the invention renders possible more or less uninterrupted writing even in the case of rather large machines in which the individual movements that serve to bring the type carriers into the writing or casting position require rather a long time. The carrying out of the invention is possible, more particularly when employing a register box or the like as described in another pending application, Ser. No. 106,668.

50 The invention is illustrated by way of example in the accompanying drawings in which:—

Figs. 1 and 2 are side elevations, partly in section, of apparatus according to the invention, in two different positions,

Fig. 3 is a plan of the apparatus according to Fig. 1.

Fig. 4 shows in side elevation a device which serves for the moving of parts of the apparatus illustrated in Figs. 1 and 2, and

Fig. 5 is a cross section through part of the apparatus illustrated in Figs. 1 and 2.

Fig. 6 shows the method of using the invention in one of the applicant's typewriters.

In the drawing 1 denotes a bar moved directly from a key 1^a or else indirectly with the aid for example of an eccentric, or cam, 1^b the said bar being equipped with projections or teeth 2^a and 2^b. The projections 2^a have in Figure 1 rocked cross-bars 3^a extending through the machine, while the cross-bar 3^b has not been moved by the projection 2^b because the latter, as explained in another of the present applicant's specifications, Ser. No. 106,667, passes through a corresponding groove in the cross-bar 3^b. The cross-bar 3^a as well as further cross-bars, not shown, likewise remain unmoved by the bar 1, because the bar 1 has no projection 2^a or 2^b at all for these cross-bars. From the cross-bars 3^a are moved hammers 4^a which are constructed as single-armed levers and which are arranged with other hammers 4^b on a carriage 5 travelling through the machine step-wise like the carriage of a typewriter. 6^a, 6^b are double-armed levers which are rocked by the hammers 4^a out of a position shown by the levers 6^b into a position shown by the levers 6^a. The levers 6^a and 6^b are rotatably journaled on strips 7. The number of strips provided is equal to the maximum possible number of letters in a line. These strips 7 are so arranged as to be movable up and down jointly with the frame 8, 9. The frame 8, 9 may for example be lifted, after the key actuation of a line, from the position shown in Fig. 1 into the position shown in Fig. 2. The positioned preparatory registering levers 6^a then meet registering levers 13^a, while the registering levers 6^b do not bring about any movement of the adjusters 13^b.

The strips 7 are connected by rods 10 and carry thickened parts or bosses 11 against which the adjusting mechanisms 6^a can bear. Instead of bosses 11 in alternation with levers 6^a, 6^b, such levers themselves may be employed adjacent to each other as shown at the right hand end of Figs. 1 and 2, to

act as stops. The levers 6^a, 6^b are provided according to Fig. 5 with a bend 12, with which they can strike against the adjusters 13^a, 13^b which are likewise constructed as double-armed levers. The registering levers 13^a, 13^b are located on bars 14 the number of which corresponds to the number of strips 7 and which, together with the frame 15, 16 can be moved in the direction of the arrow *a*, Fig. 2. The positioned registering levers 13^a may for example take with them movement devices 30, 31 (Fig. 6) for magazines 32 or push bars 33. The registering levers 13^a, 13^b are supported upon continuous or discontinuous rods 17. For the purpose of holding the levers 6^a and 6^b, as well as the levers 13^a and 13^b, springs 18 (Fig. 5) are provided. The carriage 5 runs upon rollers 19 and is held in its longitudinal direction by a roller 20. 21, 21 are plates provided on both sides of the machine, in the oblique slots 22 of which engage pins 23 on the frame 8, 9. These slots extend obliquely upwards and downwards and can therefore bring about the movement of one frame 8, 9 upwards and of another corresponding frame downwards. 24 is a plate with slots 25, which can bring about the release of the positioned levers 6^a. The slots 25 are such that when the releasing plate moves in the direction of the arrow *b*, Fig. 1, they bring about a transference of the levers 6^a into the position corresponding to the levers 6^b, while they are so long that they render possible a return movement of the releasing plate into the position of Figure 1, without the levers 6^a, 6^b taking part in this return movement. 26 (Fig. 4) is a group of teeth on one of the plates 21 which co-operates with a toothed wheel 27 which is movable from the motor drive and thereby brings about the movement of the frames with the levers 6^a, 6^b. The movement of the frames 7, 8, 9, with their provisionally adjusted registering levers 6^a, out of the position of Figure 1 into the position of Figure 2 and the return movement of this frame into the position according to Figure 1 with simultaneous release of the preparatory registrations may be effected instantaneously after starting the drive, so that after the starting of the motor the typist can go on writing immediately. For example, one line may lie ready for printing on the table 34, a second may be simultaneously registered by the levers 13^a and 13^b, while the typist is actuating the keys for a third line and bringing it to the preparatory registering levers 6^a, 6^b.

60 I claim:—

1. In a machine of the character described, a keyboard, a plurality of series of rows of selectable abutments, and means for selecting in one series an abutment in each said rows in accordance with the depressing of

the keys of the said keyboard, another series of rows of selectable abutments being adapted to be selected in accordance with and by means of the selected abutments of the said first series of rows of abutments.

2. In a machine according to claim 1 the abutments of the first series of rows of abutments consisting in rockable levers.

3. In a machine according to claim 1 the abutments of the second series of rows of abutments consisting in rockable levers.

4. In a machine according to claim 1 the abutments of the said first and second series of rows of abutments consisting in rockable levers.

5. In a machine according to claim 1, the abutments of the said first series of rows of abutments consisting in rockable levers each being provided with a broad part adapted to engage an abutment of another series of rows of abutments.

6. In a machine according to claim 1, the abutments of the said second series of rows of abutments being adapted to be engaged by the selected abutments of the said first series.

7. In a machine according to claim 1, the abutments of the said second series of rows of abutments being adapted to be moved in the direction of a said row, and members adapted to be engaged and moved by means of the selected abutments of the said second series.

8. In a machine according to claim 1, the selected abutments of the said first series being adapted to be restored immediately after the selecting of the abutments of the said second series.

9. In a machine according to claim 1 means for moving the said first series after the selection of the abutments of its rows toward and from the said second series.

10. In a machine according to claim 1 a carriage adapted to travel through the machine and to select the abutments in the said first series of rows in accordance with the subsequent depressing of keys of the said keyboard.

11. In a machine according to claim 1, the abutments of the said second series of rows of abutments being adapted to be moved in the direction of a said row, members adapted to be engaged and moved by means of the selected abutments of the said second series, and a series of movable type-bar magazines, each member arranged to move a magazine.

12. In a machine according to claim 1, the abutments of the said second series of rows of abutments being adapted to be moved in the direction of a said row, members adapted to be engaged and moved by means of the selected abutments of the said second series, a series of type bars, and a series of type bar movers, said members being each arranged to move a type bar mover.

13. In a machine according to claim 1, the selected abutments of the first series being adapted to be restored immediately after being selected by the abutments of the said second series, and a restoring plate arranged to be moved to-and-fro for restoring the abutments of the first series.
14. In a machine according to claim 1, a traversable carriage to select the abutments in the said first series of rows in accordance with the subsequent depressing of keys of the said keyboard, and a plurality of series of rows of said abutments being arranged on each side of the said carriage.
15. In a machine according to claim 1, a traversable carriage to select the abutments in the said first series of rows in accordance with the subsequent depressing of keys of the said keyboard, a plurality of series of rows of said abutments being arranged on each side of the said carriage, and means for moving the one series toward and from the other series after the selecting of the abutments in accordance with the depressing of the keys of the keyboard.
16. In a machine according to claim 1, a traversable carriage to select the abutments in the first series of rows thereof in accordance with the subsequent depressing of
- keys of the said key board, a plurality of series of rows of said abutments being arranged on each side of the said carriage, and a movable plate on each side of the machine adapted to move two series toward and from the other series after the selecting of the abutments in accordance with the depressing of the keys of the keyboard.
17. In a machine according to claim 1, a traversable carriage to select the abutments in a series of rows thereof in accordance with the subsequent depressing of keys of the said keyboard, a plurality of series of rows of said abutments being arranged on each side of the said carriage and on each side of the machine, a movable plate on each side of the machine adapted to move two series toward and from the other two series after the selecting of the abutments in accordance with the depressing of the keys of the keyboard carriers joined with the first series, projections on the carriers, and oblique slots in the said plates adapted to engage and to move the said projections so as to move the said carriers to and fro relatively to each of the second series.

In testimony whereof I affix my signature.

ARNOLD AUGUST EGLI.
